ABSTRACT

Charge carriers are emitted from the surface of a heterojunction region which is formed within the film-like body of a semiconductor material. The emitting region is defined by an interface which is generally semicircular in cross-section or has at least a substantial portion neither parallel nor perpendicular to the surface of the film-like body. The thickness of the film-like body is somewhat greater than the depth of the emitting region so that continuous uninterrupted and generally semicylindrical inner and outer depletion regions exist adjacent the interface. When a voltage is applied across the film-like body and hence across the emitting region, the depletion regions distort in a particular fashion and produce an electric field within the emitting region. Electrons crossing the interface are "heated" by this field to a degree permitting electron emission from the surface of the emitting region. In addition, electrons crossing the interface, due to the generally semicylindrical shape of the emitting region, are nonuniformly distributed within the emitting region. This space charge effect not only enhances the heating of the electrons as they approach the emission surface, but, in addition, tends to lower the surface work function. The electron emission may be varied by altering the voltage applied across the junction.

RELATED APPLICATION

This application is a continuation-in-part of application Ser. No. 220,064, filed Jan. 24, 1972, and now issued as U.S. Pat. No. 3,821,773.

BACKGROUND OF THE INVENTION

It is desirable for a low temperature solid state electron emitter to provide a long service life, to be of low cost construction, to be operable within a wide range of temperatures and to operate with relatively low applied voltages. It is further desirable for such an emitter to provide high beam currents, high current densities, high current and power efficiencies and also to be operable without requiring a high or good vacuum. In addition, the emitter should not require the use of any dangerous or poisonous materials.

Existing cold solid state electron emitters are generally of three basic types. These are the field emitter, the tunnel-type emitter, and the negative affinity emitter. Each of these emitters is lacking in providing one or more of the above desirable advantages. For example, the field emitters require a high voltage power source and a high vacuum. These emitters also have a short service life and provide low electron currents. The tunnel emitters and the negative affinity emitters have low efficiencies compared to the emitter of this invention and negative affinity emitters employ the element caesium which is a dangerous and difficult material to handle. Furthermore, all of these emitters are expensive to construct.

In recent years, experimental work on another form of cold solid state electron emitter has been conducted by M.I. Elinson et al. in U.S.S.R. The results of this work are reported in a 1965 issue of a U.S.S.R. publication entitled *Radiotekhnika* and *Elektron* (pages 1290-1296) and indicate that "hot electrons," i.e., electrons having an energy level above the bottom of the conduction band, are emitted from specially prepared high resistance regions in a film of tin oxide semiconductor material (SnO_2) when a voltage is applied across the high resistance region. This work further shows that electron emission from the high resistance region is distinguished by a high emission efficiency at low voltages when compared to existing types of cold cathode solid state emitters.

Subsequent experiments on electron emission from tin oxide films have been conducted by A. M. Soellner et al. at the University of Arkansas under a research program supported by the Avco Corporation. Some of the results of these latter experiments are reported in the February 1968 issue of the *Journal of Applied Physics* and confirm that when a voltage is applied across a tin oxide film located within a vacuum, a narrow high resistance region forms, sometimes adjacent the negative metal contact, and electrons are emitted from this region.

Other studies relating generally to cold solid state electron emitters are reported in the following publications:

  - 35 It has also been found desirable for display devices to have a long service life, to be of low cost construction, to be operable over wide temperature ranges, to operate with relatively low applied voltages, to use a minimum of electrical power, to have high brightness, and to have small overall volume. The existing display devices are generally of four basic types.
  - 40 These are the cathode ray tube, light emitting diodes, gas tubes, and liquid crystals. Each of these display types is lacking in one or more of the desired advantages.
  - 45
- SUMMARY OF THE INVENTION**
- The present invention is directed to an improved low temperature solid state charge carrier emitter which provides all of the advantages mentioned above in addition to providing for controlling the emission of charge carriers into a vacuum, gas, liquid or solid material. Specifically, the emitter of the invention provides for the emission of electrons, as one form of charge carriers, from a particular form of junction in response to a voltage applied across the junction. The electron emitter of the present invention is adapted for emitting electrons both across a solid-vacuum barrier as is required in cold cathode displays, photo cathodes, RF amplifiers and oscillators and across a solid-solid barrier as is required in injection lasers, electron beam injection transistors, variable barrier thin film transistors, and solid state display devices.
- For purposes of description, the structure and configuration of an electron emitter constructed in accordance with the invention are illustrated with this structure taking the form of a non-stoichiometric tin

dioxide-tin monoxide heterojunction. However, it is to be understood that the invention relates to a charge carrier emitter and may be formed of other semiconductor materials according to the performance characteristics desired for the particular application.

In general, the embodiment herein disclosed includes a thin film-like body of tin dioxide which is applied to a substrate such as quartz, glass, or alumina. An electron emitting region in the form of an elongated curvilinear or generally semicylindrical junction is formed within the upper surface portion of this tin dioxide body and consists generally of tin monoxide. The depth of the generally semicylindrical interface defining the junction between the tin dioxide and tin monoxide materials is approximately one-half the thickness of the film in the illustrated embodiment of the invention, with the portion of the film remaining below the interface defining a narrow throat region in a conduction path existing between two electrodes or contacts attached to the film material on opposite sides of the junction region. Semicylindrical inner and outer depletion regions exist within the tin dioxide and tin monoxide materials adjacent their interface. The electrodes or contacts on the film are positioned so that their respective depletion regions do not intersect with the outer depletion region in the tin dioxide material.

When a voltage is applied across the electrodes or contacts attached to the film-like body, the energy barriers associated with the depletion regions and the junction of the tin dioxide and tin monoxide materials shift to an asymmetric condition resulting in charge carrier flow across the junction and into and out of the tin monoxide emitting region. The application of voltage to the electrodes or contacts also modifies the shape of the depletion regions in the tin dioxide and tin monoxide materials adjacent the junction and creates an electric field internal to the tin monoxide emitting region. This internal electric field acts upon the electrons crossing the junction into the tin monoxide region and excites these electrons into a higher energy state.

As a result of the generally semicircular configuration of the junction, these energetic or hot electrons have component of momentum that equals or exceeds the surface or interface barrier so that electrons are emitted from the tin monoxide material. In addition this internal electric field will increase near the emitting surface, more specifically the field will increase near the origin of the semicylindrical region. This increasing field not only enhances the excitation of electrons into higher energy states, but tends to lower the vacuum barrier due to the increased concentration of charge near the surface and particularly near the center of the emission region.

The present invention is also directed to display or indicator devices incorporating an emitter as described above. For example, the invention provides for a cathode ray tube having a cold electron source which eliminates the need for a thermionic cathode. The invention further provides a cold cathode surface for a spatially addressable or controllable display device such as the device sold under the trademark Digiscan, and also provides means for fabricating flat screen displays, both vacuum and solid state as well as

alpha-numeric displays or indicator devices, both vacuum and solid state. In addition, the invention provides for producing small indicator lights, both vacuum and solid state.

Other features and advantages of the invention will become readily apparent to those skilled in the art from the following descriptions and accompanying drawings.

10 BRIEF DESCRIPTION OF THE DRAWINGS

FIG. 1 is a perspective view of a low temperature solid state electron emitting device or cathode constructed in accordance with the invention and showing portions of the device greatly enlarged for purposes of illustration;

FIG. 2 is an enlarged cross-section of the electron emitting device shown in FIG. 1 as taken generally along the line 2-2 in FIG. 1 and illustrating its zero bias voltage condition;

FIG. 3 is a cross-sectional view of the electron emitting region of the electron emitting device shown in FIG. 2 and showing a representation of the electrons flowing into the emitting region and the electric fields existing in the emitting region during operation of the device;

FIG. 4 is a conduction band energy diagram taken across the FIG. 2 electron emitting region along a particular path AB and before a voltage is applied to the device;

FIG. 5 is a fragmentary section similar to FIG. 2 and illustrating, in a greatly exaggerated form, the deformed depletion regions around the electron emitting region after a voltage is applied to the device;

FIG. 6 is a conduction band energy diagram taken across the FIG. 5 emitting region along the path AB after a voltage is applied to the device;

FIG. 7 is a fragmentary view similar to FIG. 2 and illustrating the application of the device for emitting electrons directly into a solid semiconductor in accordance with another embodiment of the invention;

FIG. 8 is an enlarged section similar to FIG. 7 and showing a solid state display modification in accordance with the invention;

FIG. 9 is a diagrammatic illustration of the emitting device of the invention and arranged as a cathode within a cathode ray tube;

FIG. 10 is a diagrammatic illustration of a plurality of emitting devices arranged to form a cathodic surface for a spatially addressable or controllable display;

FIG. 11 is a diagrammatic illustration of one method of fabricating a cathode surface using a plurality of emitting devices of the invention;

FIG. 12 illustrates another method of fabricating a cathode surface using the emitting devices;

FIG. 13 is a perspective view similar to FIG. 1 and showing a low temperature solid state emitting device constructed in accordance with another embodiment of the invention;

FIG. 14 illustrates another method of using emitting devices as a cathodic surface for a spatially addressable or controllable display;

FIG. 15 is a sectional view illustrating another method of fabricating a cathode surface using a

plurality of emitting devices of the invention;

FIG. 16 is a plan view of cathode surface shown in section in FIG. 15;

FIG. 17 is a sectional view illustrating another method of fabricating a plural cathode surface in accordance with the invention;

FIG. 18 is the plan view of the cathode surface shown in section in FIG. 17;

FIG. 19 is an enlarged section similar to FIG. 2 and illustrating the effects of a buried control conductor;

FIG. 20 illustrates another method of using plural emitting devices as a cathodic surface for a spatially addressable or controllable display;

FIG. 21 illustrates a method of fabricating a phosphor conductor screen for use in a spatially addressable display;

FIG. 22 illustrates a solid state spatially addressable or controllable display using a plurality emitting devices as a cathodic surface in accordance with the invention; and

FIG. 23 is a conduction band energy diagram similar to FIG. 6 but illustrating the injected space charge effects.

DESCRIPTION OF THE ILLUSTRATED EMBODIMENTS

The solid state electron emitting device shown in FIG. 1 includes a supporting substrate 15 which may be a sheet of quartz glass or alumina. A film-like body 16 of a wide band gap semiconductor material is deposited on the substrate 15 in an hourglass or bow tie configuration as shown generally in FIG. 1 to form a narrow constricted portion 17; this semiconductor material is a non-stoichiometric tin dioxide (SnO_2) which is an n-type semiconductor. As will be explained later, the body 16 may be constructed of other semiconducting materials and may also be formed in configurations other than that shown in FIG. 1. A pair of parallel-spaced contacts 18 and 19 extend along opposite edges of the body 16 and may be formed by depositing a film of gold on the semiconductor material of the body 16. While the two contact configuration of the device is illustrated in FIG. 1 for purposes of simplification, additional contacts may be used on the device.

An elongated electron emitting region 20 projects into the thickness of the body 16 from the upper surface 21 of the body and is formed of a narrow band gap semiconductor material consisting of generally tin monoxide (SnO). The junction between the emitting region 20 and the body 16 define a heterojunction interface 22 which is generally semicircular in cross-sectional configuration and extends along the restricted portion 17 of the body 16 parallel to the contacts 18 and 19. In FIG. 2, the emitting region 20 is positioned midway between the contacts 18 and 19, but it may be located closer to one of the contacts 18 or 19 in other embodiments of the invention. While the emitting region 20 is shown in FIG. 1 to be precisely half-cylindrical and precisely defined as to horizontal dimensions, the region will usually be graded and only approximately half-cylindrical.

The semicylindrical configuration of the interface 22 assures that a substantial portion of the interface extends neither parallel nor perpendicular to a center

reference plane P (FIG. 2) of the emitting region 20 is shown in FIG. 1 to be precisely half-cylindrical and precisely defined as to horizontal dimensions, the region will usually be graded and only approximately half-cylindrical.

The semicylindrical configuration of the interface 22 assures a substantial portion of the interface extends neither parallel nor perpendicular to a center reference plane P (FIG. 2) of the emitting region 20. Thus a plane tangent to the interface 22 at any point other than the points X, Y and Z, extends angularly or forms an obtuse angle with the reference plane P. This assures that the electric field generated internally in the emitting region 20 has components perpendicular to the emitting surface 25 which is illustrated in FIG. 2 as being flush and coplanar with the upper surface 21 of the body 16.

As illustrated in FIG. 2, a continuous semicylindrical negative inner depletion region 28 exists on the emitting region 20 side of the interface 22, and a continuous positive outer depletion region 30 exists on the film-like body side of the interface 22. These depletion regions 28 and 30 are of generally uniform width when the device is in a zero bias condition as shown in FIG. 2 and must contain equal and opposite amounts of electric charge. In FIG. 2 the depletion regions are shown as generally semicircular in cross-section; however, depending upon the emitter dimensions such as the radius R and the film thickness T, these depletion regions may be deformed. In particular, the inner depletion region 28 tends to be of width R while the outer depletion region 30 tends to flatten in the throat region. However, in the following descriptions of the embodiments, the depletion regions are substantially as shown. The energy band diagram of FIG. 4 is taken across the emitting region 20 along paths extended from A to 0 and from 0 to B where A and B are located on the interface 22 and 0 is located at the surface 25. The abrupt changes in the energy level at the points A and B in this diagram with reference to the bottom of the electron conduction band 38, result from the different band gaps of the materials forming the body 16 and the emitting region 20. The effects of surface and interface states, which will somewhat modify the FIG. 4 idealized energy band diagram, are not considered.

As is apparent from FIG. 4, the energy level of the conduction band through the emitting region 20 inwardly of the inner depletion region 28 is substantially constant. The energy barrier at the surface 25 of the emitting region 20 is represented by a line 40. The short inclined line 42 at the top of the line 40, represents the vacuum energy level due to a voltage V_2 which may be applied to the collector 32 when the device of FIG. 2 is energized. In this idealized case such effects as Schottky Effect have not be considered.

When a voltage is applied across the contacts 18 and 19 in FIG. 2 and hence across the emitting region 20 in the polarity shown in FIG. 2, a flow of current is produced in the conduction path 50 between the contacts 18 and 19. The voltage drop resulting from this current flow causes each point on the body side of the interface 22 to be at a different electric potential. Most of the voltage drop along the conduction path 50 occurs in the body region immediately

adjacent the outer depletion region 30 since this portion of the body has the highest resistance.

Even though each point on the body side of the interface 22 is at a different electric potential, it is necessary for any given point on the surface 25 of the emitting region to have an electrical potential which is single valued or has the same value regardless of the path used in reaching the point. For example, the potential at point O' in FIG. 3 must be the same regardless of whether the point O' is reached by starting at the point A or the point C, in FIG. 3. The potential along the path A-O in FIG. 3 is defined by the left hand portion of the FIG. 4 energy diagram, i.e., the portion up to the base of the line 40 while the potential along the path O-B in FIG. 3 is defined by the right hand portion of the FIG. 4 energy diagram, i.e., the portion to the right of the base of the line 40. The difference in the bottom of the conduction band energy level in the FIG. 4 and FIG. 6 drawings is the result of different potentials at the points A and B in FIG. 4 and results from the voltage drop along the path 50 shown in FIG. 2. In FIG. 6 the space charge effects have not been included.

For the potential variation illustrated by the energy diagram of FIG. 6 to exist in the FIG. 3 structure, it is necessary that an electric field internal to the emitting region 20 exist; this electric field being associated with a charge field. Analysis of the semi-circular emitting region 20 shown in FIGS. 2 and 5 shows that with a voltage applied across the contacts 18 and 19, a charge field exists in the form of the altered depletion regions shown at 28 and 30 in FIG. 5 and that electric fields also exist in the emitting region 20 as illustrated by the vectors F_1-F_8 in FIG. 3. It is notable that the configuration of the depletion regions shown in FIG. 5 differs sharply from the depletion regions associated with a conventional n-p-n transistor-like structure. In the transistor-like structure, charge neutrality across both the n-p junction and the p-n junction is strictly maintained if the bias voltage is not too large. The magnitudes of the negative and positive charges associated with the forward biased junction (n-p) are reduced by equal amounts, and the magnitudes of the charges associated with the back or reversed biased junction (p-n) are increased by equal amounts. Thus charge neutrality is maintained across each individual junction as well as across both of the junctions.

As shown in FIG. 5, the depletion regions (or charge concentration) of the junction in the present invention are made asymmetrical by a redistribution of charge throughout the depletion regions so that the positive charge associated with point X has decreased while the negative charge has increased by the application of a bias voltage to the device. Thus, charge neutrality across the forward biased portion of the junction is violated. In like fashion, in the back biased portions of the junction (p-n) of the present device, as shown in FIG. 5, the depletion regions (or charge concentration) are made asymmetrical by the application of a bias voltage in that the positive charge associated with point Z is increased while the negative charge concentration decreases. These charge concentration asymmetries are such that although neutrality across the individual junction (forward or reversed biased) is violated, charge

neutrality along any path such as A-O-B of FIG. 5 is maintained. At some point C located approximately halfway between the region of maximum charge asymmetry at X and Z, the charge concentrations are equal. Point C is thus the point dividing the forward and reversed biased regions of the junction.

The difference in the depletion region or charge concentration behavior in the normal n-p-n junction arrangement and the present invention device is attributed to the continuous nature of the depletion regions in the present invention device and to the continuous variation in the biasing of the junction due to the adjacent conduction path of the device as compared with the interrupted nature of the depletion regions of the normal n-p-n junction device and the discontinuous bias conditions. That is, the positive charge outer depletion region 30 in FIG. 5 is continuous all around the interface 22 from the point X to the point Z without being interrupted by omission of the bottom part of the interface (the portioning the point Y for instance). The depletion regions 28 and 30 in the FIG. 5 device are also made continuous and free of intersection by the depletion regions 34 formed around the contact electrodes 18 and 19 when voltage is applied to the device. That is, the electrodes 18 and 19 and separated from the emitting region 20 by a relatively large distance so that the depletion regions 34 do not intersect with the depletion regions 28 and 30.

The electric field internal to the tin monoxide emitting region 20 resulting from the asymmetrical charge distributions illustrated in FIG. 5, is represented by the family of vectors F_1-F_8 shown in FIG. 3. This family of vectors represents the magnitude and direction of force exerted on a unit negative charge by the asymmetrical charge distributions in the two depletion regions 28 and 20. As illustrated in FIG. 6, the internal electric field is assumed sufficiently small that "band bending" or a significant variation in the Fermi level in the tin monoxide material does not occur. Furthermore, in FIG. 6 the space charge effects have been assumed to be negligible.

The electric field represented by the vectors F_1-F_8 , has its maximum amplitude along the horizontal vectors F_1 and F_8 , which are coincident with the surface 25 in FIG. 3, and has its minimum value at a null vector (not shown) which is of zero length and located parallel to the reference plane P at the point O' in FIG. 3. The magnitude of the individual vectors in the family F_1-F_8 is determined by the relation:

$$|\text{Electric Field}| \sim \int Q dr$$

where Q represents electric charge, and r represents the distance along the path starting at some point of zero charge outside the region 20 and ending at the point O'.

Since the horizontal electric field vector F_1 in FIG. 3 has the maximum magnitude but a zero vertical component, and since the zero length or null electric field vector has the maximum vertical component but has zero magnitude, there is a vector located between the vectors F_1 and the null vector which will have a maximum vertical component and will hence be the most effective to accelerate electrons

to overcome the surface barrier denoted by the line 40 in FIG. 6 so that electron will be emitted from the surface 25.

The direction of maximum electron emission from the surface 25 is defined by a combination of the electric field vector having a maximum vertical component and also by the magnitude of electron flow across the interface 22. The magnitude of electron flow over the interface barrier 22 is represented in FIG. 3 by the arrows E_1 , E_2 and E_3 . This flow being a maximum at E_1 due to the maximum reduction in charge density in depletion region 30 at point X reducing to zero at point C (E_3). The electron flow is zero at point C since as noted before, this is a point of zero bias.

The interaction of the field vectors and the variation of the number of electrons crossing the interface barrier gives a preferential direction to the electron emitted into the vacuum. This preferential direction is indicated in FIG. 3 by line 51. The arrows E_1-E_2 represent the electron flow from all mechanisms such as thermionic, tunneling, etc., by which charge carriers can cross a barrier.

The net difference in electrons flowing into the emitting region 20, represented by the family E_1-E_2 , and the electrons flowing out of the emitting region 20, represented by the family E_3-E_4 , represents the electrons emitted from the surface 25 assuming recombination currents, etc., are zero.

The curve 53 in FIG. 3 represents the angular distribution of electrons emitted from the surface 25, the greatest number of electrons being at the peak of this curve along the arrow 51 with decreasing numbers being directed at angles slightly removed from this peak. As illustrated by the curve 53, the number of electrons emitted at a smaller angle than the arrow 51 with respect to the reference plane P decreases more rapidly than those directed at an angle greater than the arrow 51. The point O' on the surface 25 represents the point of maximum emission of electrons and is displaced by a very small distance from the geometric center O of the emitting region 20. This separation is shown greatly exaggerated in FIG. 3, and is the result of the asymmetrical charge distributions. The point O' shown in FIG. 3 is the point common to all electric field vectors F_1-F_8 , and the separation between $O-O'$ increases with an increase in the voltage applied across the device.

The electrons crossing the interface barrier 22 are illustrated in FIG. 6 by the distribution 46. These electrons are shown as "hot" relative to the material of region 20. However, this is not important, since these electrons, as noted before, are due to many emission mechanisms such as thermionic, tunneling, etc., and the actual distribution is quite complex. Regardless of the initial distribution 46, the electron energy distribution will be essentially drifted Maxwellian at the surface barrier 40 and at the right (FIG. 6) interface barrier 52. This Maxwellian distribution at the barrier 52 is represented by the distribution 48, and the line 49 represents the average electron energy. The distribution 48 is controlled by the internal electric field due to the voltage applied across the device. In particular, the electron's average energy, line 49, is controlled relative to both the surface barrier 40 and the interface barrier 52 by the

application of the voltage V_1 across the contacts 18 and 19.

Electron emission from the surface occurs when the electrons in the emitting region 20 have acquired sufficient energy from the internal electric field to overcome the surface barrier 40. The curvature of the generally cylindrical interface 22 effectively concentrates the electron flow towards the center O' of the region 20 so that the electrons are primarily emitted from a centralized portion of the region.

This concentration of electrons as they approach the surface at O or O' will result in other effects which will enhance electron emission. These space charge effects are of two types. To maintain current continuity, it is necessary for the electric field to be a maximum near the surface 25 and specifically at the point O' of FIG. 3. This will modify the energy band diagram of FIG. 6 as illustrated in FIG. 23. Furthermore the vacuum barrier 40 of FIG. 6 results from the surface traps or imperfections, and the formation of a dipole layer at the surface. The increased charge concentration near the point O' of FIG. 3 will modify both the number of trapped surface charges and the dipole layer in the vicinity of O' , thus the vacuum barrier 40 will be reduced.

As illustrated in FIG. 5, the thickness T of the film-like body 16 is made somewhat greater than radius R of the semicylindrical region 20 so that the outer depletion region 30 is continuous and uninterrupted around the interface 22. Preferably, the radius R should be between .1 and 1 micron and should not be greater than $\frac{3}{4}$ of the body thickness T at the reference plane P. However, if the radius R exceeds $\frac{3}{4} T$, the device will operate but at reduced emission currents and will require a higher film voltage V_1 (FIG. 2).

If the body thickness T is increased at the reference plane P to a value substantially greater than the radius R , the resulting greater cross-section area in the throat region of the conduction path 50 effectively reduces the electric field in the emitting region 20, and results in an electron emitting device having a higher threshold voltage and lower efficiency as an emitter. It is also found that the threshold voltage increases as the radius R increases. As a maximum practical limit, the radius R should not exceed 25 microns. It is also important for the contacts 18 and 19 to be spaced at a sufficient distance from the junction 20 so that their corresponding depletion regions 34 do not intersect with the outer depletion region 30 surrounding the interface 22.

In fabricating the electron emitting device shown in FIGS. 1 and 2, it is preferable to deposit a tin dioxide film on a substrate such as quartz or alumina until the film has a thickness approximately twice the desired value of the radius R . For optimum performance, the film thickness should be less than one micron. After deposition, the film is placed in a reducing atmosphere and is electrically heated by applying a voltage across the contacts 18 and 19. The purpose of the electrical heating is to cause the formation of emission region 20.

The voltage applied to the contacts 18 and 19 may be either D. C., A. C. or cyclic D. C., that is, the polarity being reversed during the forming process. There are two forming techniques which result in

optimum emitters. The first forming process consists of applying approximately ten volts to the contacts 18 and 19. This voltage could be either D. C. or ten volts RMS A. C., and the frequency of the A. C. is not critical. While current from this ten volts is flowing through the film, the current is monitored and the voltage is slowly increased until, without a further increase in voltage, the current continues to rise and then suddenly drops usually to about one tenth of the value before the current continued to rise without a voltage increase.

The sharp drop in the current flow indicates a corresponding sharp increase in the resistance of the film. This rapid increase in resistance results from the formation of the region 20 within the narrow constricted portion 17 of the body 16. At this time outgassing occurs, and if V2 of FIG. 2 were energized, electron emission would be observed. Also, at this time, the voltage V1 is maintained constant and the emitter is allowed to season or age for two to four hours. The film current will slowly increase and the emission current will also increase. During this aging cycle, the emission current is noisy. As the emitter ages, the film current will reach a maximum and then decrease. When the film current decreases, the emission current will increase usually by one to two orders of magnitude. After operating for approximately ten hours, the emission current noise decreases materially.

Another method of forming the emission region 20 is to preset the voltage V1 at a level corresponding to $\frac{1}{4}$ watt dissipation. This voltage is then applied in a square wave to contacts 18 and 19. The duration of the pulse is not critical. If formation of the emitting region 20 does not occur, then V1 is reset to $\frac{1}{2}$ watt dissipation and the process is repeated. This continues until the emission region 20 forms. The aging cycle previously described is then initiated.

As mentioned above, the electron emitting device is illustrated in the form of a tin dioxide-tin monoxide heterojunction. However, the emitting device may be formed of other semiconductor materials and by other fabrication techniques, providing the general geometry and configuration of the region 20 are maintained in relation to the body 16. It is also possible to form the electron emitting region 20 from a metal alloy or an insulator in place of the narrow band type semiconducting material.

While the emitting device disclosed in FIGS. 1-6 relates to the emission of electrons from the surface 25, the described device may also be used for emitting or ejecting electrons directly into another solid. Thus referring to FIG. 7, the emitting surface 25 of the junction 20 is located adjacent another film-like element 55 of a semiconductor material which receives a controlled charge through a lead 56 which is connected to a voltage source V₃. In FIG. 7, the metallic electron collector 32 is located adjacent the other side of the semiconductor element 55 forming by way of illustration a Schottky barrier between the element 55 and the collector 32. Thus the emission of electrons from the region 20 cannot only be controlled or varied by changing the voltage across the contacts 18 and 19 and/or on the collector 32, but may also be controlled by changing the voltage V₃ on the element 55. At the present time, all of the specific

applications of this embodiment for emitting electrons directly into another solid are not certain. However, it is believed that this embodiment will be useful in construction of improved injection lasers, new and improved austo-electric and transferred electron devices, as well as variable barrier transistors and similar electronic components. It is also to be understood that in the FIG. 7 embodiment of the invention, the emitter may be constructed so that holes form the majority current carriers instead of electrons.

The embodiment of the charge carrier emitting device in FIG. 2 may be modified so that the collector 32 and the voltage V2 is eliminated. Upon the application of the voltage V1 to contacts 18 and 19, electrons will be emitted into the vacuum. These emitted electrons will be collected by the surface 21 adjacent the positive contact 19.

Another embodiment of the charge carrier emitting device similar to that shown in FIG. 7 is illustrated in FIG. 8. In this embodiment, the surface 25 of the emitting region 20 is covered by a thin film or layer of dielectric material 58, and over this dielectric material other layers are deposited, such as, for example, a phosphor layer 59, a collector 60 and a ceramic cover 61 are shown. However, other layers could be used and these could include semiconductor and conductors as well as the phosphor shown. In this illustration, the collector 60 is tin oxide, a transparent semiconductor.

While the emitting devices disclosed in FIGS. 1-6 relate to a device having a body 16 fabricated with a wide band gap n-type semiconductor, an emitting device may also be fabricated in accordance with the invention by using narrow band gap, either n-type or p-type, semiconductor materials. Emitting devices using p-type material for the body 16 are particularly important in the embodiment disclosed in FIG. 7 for photo-sensitive electron emitting devices.

As mentioned above, the emitting device of the present invention may be chemically formed by locally heating the film-like body portion which is to form the electron emitting region in a reducing atmosphere as specified. A solid state emitter device may also be fabricated by other techniques depending on the materials selected for both the body 16 and the region 20. Usually the semiconductor body 16 of the solid state emitter is fabricated by using standard techniques such as chemical vapor deposition or epitaxial formation. Preferably, the body is then annealed, especially if the semiconductor material is one that exists in more than one chemical combination, e.g., A_xB_y or A_xB_{y-n}, such as some of the oxides and chlorides. By annealing in the presence of a suitable oxidation or reducing agent, the semiconductor properties can be controlled.

In addition to chemical formation of the region 20 by electrically heating the body 16, this region may also be formed by etching a small region of the semiconductor body 16 to form a generally V-shaped trough or groove in the upper surface 21 of the semiconductor body 16. The region 20 material, which may be either a semiconductor or a metal, is then deposited in the etched groove by a method such as vapor deposition or sputtering. The region 20 may also be formed by ion implantation of the

region 20 material, using conventional implantation techniques.

One application of an emitting device or cold cathode of the invention is in place of the conventional thermionic cathode normally employed in a cathode ray tube. In this embodiment, which is illustrated in FIG. 9, only one emitting device or cathode is shown, however, multiple cathodes would normally be included, for example, such as in a color cathode ray tube. The reference numbers 63, 66, 67, 68 and 69 represent electrical connections or conductors to the cathode ray tube. The conductor 63 connects to the first accelerating grid 70, and the electrical conductors 68 and 69 connect to the charge carrier emitting device of the invention or cold cathode 72. The electrical conductor 66 connects with the second accelerating grid 70, and the conductor 71 represents all electrical connections necessary for the focusing and deflection system 73.

Conductor 67 is the high voltage connection to a phosphorous collector screen 75 which forms a wall or is adjacent a wall of an enclosure tube or surrounding envelope 76. Although not shown, other standard cathode ray tube components, such as getters, would be included in the embodiment. Furthermore, in the embodiment of FIG. 9, electrostatic deflection is illustrated, but other forms of deflection may be used, such as electromagnetic deflection.

When a voltage is applied to conductors 68 and 69, electrons are emitted from the cathode 72 generally in the direction of the phosphorous collector screen 75. The accelerating grids 70 accelerate a fraction of the emitted electrons toward the focusing and deflection system 73. These electrons are focused and deflected to excite the phosphor collector screen 75 in accordance with the voltage applied to conductors 68. Brightness or Z axis modulation in this embodiment is produced by either modulating the voltage applied to the accelerating grids 70 or by modulating the voltage applied between conductors 68 and 69 extending to the cathode 72.

In addition to the above mentioned direct cathode modulation, the embodiment shown in FIG. 9 has additional advantages over a thermionic cathode. One of these advantages is essentially instantaneous warm up. That is, the cold cathodic emission inherent in this embodiment eliminates the need for heater warm up power required in conventional thermionic cathodic devices. Another advantage in the embodiment of FIG. 9 is the improved life of the CRT. It is known that the life of thermionic cathode devices is to a large extent limited by the thermal shock associated with cyclic heating and cooling of the cathode structure. In the past, this problem has been partially alleviated by maintaining power to the cathode even when the power is turned off to other associated electronics. The cold cathode embodiment described herein does not require this continued power consumption to provide for a long service life.

An embodiment of the charge carrier emitting devices for a spatially addressable CRT is illustrated in FIG. 10. In this embodiment, a planar cathode array 80 of the charge carrier emitting devices 20 is used to allow for the emission of electrons from a planar surface of the array 80. The numbers 81 and 82 represent the electrical connections to the

cathode array 80, and electrical connections 84 extend to a spatial or scanning control unit 85. Conductor 86 extends to a control grid 88, and a conductor 89 extends to a phosphorous coated collector screen 90.

5 All of the components 80, 85 and 88 are sealed within a tube envelope 92 with the screen 90 forming one wall, of the envelope. In the embodiment illustrated in FIG. 10, the Digiscan method is used for spatial control, however, other means of spatial control of the emitted electrons may be employed.

In operation of the apparatus shown in FIG. 10, electrons are emitted from the surface of the cathode array 80 in response to voltages applied between conductors 81 and 82. The electrons are modulated by 15 the control grid 88 in response to the voltage applied to conductor 84 and are spatially filtered such that only electrons for one resolution element, as determined by the voltages applied to connections 84, pass through the spatial filter 85 and impinge on the phosphor collector screen 90. In reference to FIG. 11, the cathode array 80 consists of a plurality of emitting regions 20 which are spatially separated and are connected to parallel electrical contacts 18 and 19. Driving voltages for the emitting regions 20 are supplied by the application of a voltage to contacts 18 and 19 through conductors 81 and 82 connected to contact extensions 94 and 96. The number of emitting regions 20 is established by the CRT requirements such as resolution, illumination, uniformity, etc., and the operation of each individual emitting region 20 is as described above. The embodiment of the spatially addressable CRT using the emitter array 80 illustrated in FIG. 11, may be modified to accomplish brightness of axis modulation by the modulation of the voltage applied to contact extensions 94 and 96, thereby eliminating the need for a control element such as the grid 88 shown in FIG. 10.

Another embodiment of an emitter array suitable for the CRT shown in FIG. 10, is illustrated in FIG. 12. In this embodiment, each emitting region 95 is formed as a continuous line essentially midway between the corresponding parallel contacts 18 and 19. Each linear emitting region 95 terminates short of the contact extensions 94 and 96. One of the semi-cylindrical emitting regions 95 is generally illustrated in FIG. 13, and is formed at the bottom of a notch 98 within the surface 21 of the film 16. The notch 98 serves the same function as the hour-glass restriction 50 within the film 16 as mentioned above in connection with FIG. 1. The operation of this embodiment of a spatially addressable CRT is identical to the spatially addressable CRT described above in connection with FIGS. 10 and 11.

Another embodiment of a charge carrier emitting device or cold cathode within a spatially addressable CRT, is generally illustrated in FIG. 14. In this embodiment electrons are emitted from the surface of a cold cathode emitter array 105 in response to a voltage applied to conductors 106 and 108. The emitted electrons are accelerated across a drift space 110 due to the accelerating potential applied to the high voltage conductor 67 connected to the phosphor collector screen 75. While the electrical conductors 106 and 108 to the emitter array 105 are shown as two single connections, each conductor actually represents multiple conductors. Furthermore,

other accelerating, control, or focusing elements may be located in the drift space 110, as required. Focusing of the electrons emitted from the emitter array 105 in FIG. 14, is accomplished by proximity focusing which requires that the drift space 110 be very small, for example, on the order of .01 inch. However, specific dimensions of the space 110 are determined on the basis of the CRT requirements such as resolution, applied voltages, etc.

The emitter array 105 has an emission surface which is suitable for the spatially addressable CRT illustrated in FIG. 14. Thus referring to FIGS. 15 and 16, an array 105 of emitting devices or cathodes 20, similar to those previously described and illustrated in FIG. 11, is fabricated on the surface of an insulator or dielectric layer 122. Buried within this insulator layer 122 are conductors 124 which extend laterally or transversely to the parallel elongated contacts 106 and 108. In operation, a voltage is applied through suitable external electronics to any pair of adjacent contacts 106 and 108 which will tend to cause electrons to be emitted from a line or row of emitting regions 20 located between the contacts. If a negative voltage is applied to all but one of the embedded contacts 124, the emission is inhibited at every resolution element except the one that is located between energized contacts 106 and 108 and above the non-energized contact 124.

A more detailed construction of each embedded conductor 124 is shown in FIG. 19 in relation to a single emitting region 20. When a buried conductor 124 is energized by the application of a negative voltage to the conductor, a charge depletion region is formed in the film 16. As a result the impedance of the semiconductor material between contacts 106 and 108 increases, resulting in a decreased current flow between the contacts. Thus the emission of electrons from the adjacent emission region 20 is effectively inhibited.

Another embodiment of a cathode array 130 (FIGS. 17 and 18) is adapted for use with the spatially addressable CRT illustrated in FIG. 14. In this embodiment, an array of linear emitting regions 95 as discussed above in connection with FIGS. 12 and 13, is fabricated on the surface of an insulator or dielectric layer 122. Buried within this dielectric layer 122 are conductors 124 which extend transversely to the contacts 106 and 108. The operation of the array 130 is identical to that described above in connection with FIGS. 15, 16 and 19.

A further embodiment of a cathode array 140 for a spatially addressable CRT, is illustrated in FIGS. 20 and 21. The emitter array 140 is constructed similar to either of the arrays 105 or 130 described above in connection with FIGS. 15-19 with the exception that the buried conductors 124 are eliminated. Spatial control in one axis or direction is accomplished in the same manner as previously described, that is, by energizing any two adjacent pair of contacts 106 and 108. Control in the other axis is accomplished by inhibiting phosphorescence of a display screen 150 rather than by emission of electrons from the array 140. To accomplish this, the phosphor conductor display screen 150 (FIGS. 20 and 21) is fabricated with conducting strips 152 deposited on the tube

65

envelope 154 by a suitable process. The conducting strips 152 extend transversely to the parallel linear contacts 106 and 108 of the emitter array 140, and a phosphor layer 156 is deposited over the strips 152. When a positive voltage is applied to one of the conducting strips 152 through its contact lead 157, the area of that conducting strip directly opposite the crossing linear emission region between the energized contacts 106 and 108 will phosphor and emit light.

In accordance with another embodiment of the invention illustrated in FIG. 22, a cathode array 105 or 130 forms the emitter of a solid state display. The essential difference between this display and those previously described and illustrated, is that the vacuum drift space 110 (FIGS. 14 and 20) is replaced by a solid dielectric layer 160 which is sandwiched between the electron emitting array 105 or 130 and the phosphorous coated screen 75. The basic description of a charge carrier emitting device for injecting electrons into a solid state substance other than a partial vacuum, is described above in connection with FIG. 7.

From the drawing and the above description, it is apparent that a solid state electronic emitting device or cold cathode constructed or assembled in accordance with the invention, provides desirable features and advantages. For example, the emitting region 20 is constructed so that the interface 22 is generally semicircular in cross-section or at least a substantial portion of the interface is neither parallel nor perpendicular to the reference plane P of the emitting region. In addition, the emitting region does not extend through the body 16 so that continuous inner and outer depletion regions 28 and 30 border the interface 22. As a result of this junction geometry and configuration, and electric field is created within the region 20 when a voltage is applied across the body 16 in a lateral direction normal to the reference plane P. This internal electric field within the region 20 produces hot electrons within the region so that the emission of electrons from the surface 25 is directly proportional to the voltage drop across the throat region of the conductor path 50 and inversely proportional to the radius R of the junction 20. Thus, the size of the junction should be minimized so that electric field strengths near the 10^6 volts per centimeter believed desirable for electron emission from the tin oxide semiconductor materials, will be attained with reasonably low voltages applied across the contact electrodes 18 and 19.

Furthermore, the electron emitting device of the present invention does not require a good vacuum and it also provides for a long service life since it has no life limiting mechanisms other than heat. All prior art cold cathode emitters have at least one life limiting mechanism in addition to heat. The emitter of the present invention also provides a high emission efficiency, at least up to 50 percent, and will operate in a wide range of temperatures such as between 20° K and 700° K. As mentioned above, the body 16 may be formed of other semiconductor materials such as p-type semiconductor material. The heterojunction interface 22 described above in this specified provides for minimizing the voltage drop required across

the region 20 to produce the electric fields within the junction necessary for emission.

As also mentioned above, the described configuration of the heterojunction interface 22 insures that the fields within the junction 20 have components parallel to the reference plane P of the junction, these components are essential to assure emission of electrons from the surface 25. The depth of the region 20 relative to the thickness of the film or body T at the reference plan P is also important. As mentioned above, the thickness T of the body 16 should be at least equal to the depth or radius R of the interface 22 plus the width of the outer depletion region 30 to assure that the depletion regions 28 and 30 are continuous along the interface 22. However, it is desirable to minimize the film thickness so that the current by-passing the junction is minimized.

As also described above in connection with FIGS. 9-22, electron emitting devices or cold cathodes constructed in accordance with the invention are embodied in various forms of display devices. An additional application is in the construction of photo cathodes for use in infrared or near infrared imaging devices. The emitting device is also adaptable for producing electron beam injection transistors and RF amplifiers and self oscillating RF oscillators as commonly used in radar and radio applications. The device may also be used in the production of transferred electron devices and various instruments such as electron emitters used in electronic equipment adapted for outer space exploration. The emitting device of the invention may also be adapted for other instruments such as electron beam computer memories where low vacuum operation is desirable, and for beam readout devices such as for scanning a screen which is sensitive to infrared radiation.

While the forms and embodiments of solid state electron emitter devices and the methods of making the same herein described, constitute preferred embodiments of the invention, it is to be understood that the invention is not limited to these precise forms and embodiments and methods, and that changes may be made therein without departing from the scope and spirit of the invention.

What I claim is:

1. An improved solid state emitting and display device comprising a substrate, a cathode including a continuous film body of wide band gap semiconducting material on said substrate and having an outer surface, an emitting region projecting into said film body from said outer surface and comprising a narrow band gap semiconducting material having a resistivity higher than that of said film body material, said emitting region having an emitting surface interrupting said outer surface of said film body, a set of contacts on said film body and spaced with said emitting region therebetween for applying a voltage across said emitting region in a direction substantially perpendicular to a reference plane extending through the center of said emitting region generally normal to said outer surface, said emitting region being effective to produce a continuous emission of electrons from said emitting surface without an applied external collecting field in response to the application of a voltage to said contacts, a display screen having means for emitting

light in response to engagement of electrons emitted from said emitting region, and means for controlling the emission of light from said display screen.

2. An emitting and display device as defined in claim 1 including a plurality of said emitting regions arranged in a generally planar array, and means for selectively controlling the emission of light from a portion of said screen corresponding to each said emitting region.
3. An emitting and display device as defined in claim 1 including a plurality of said emitting regions arranged in a generally planar array, and means for selectively controlling the emission of electrons from said emitting regions.
4. An emitting and display device as defined in claim 3 wherein said means for selectively controlling the emission of electrons from said emitting regions comprise a plurality of control conductors arranged in generally parallel relation adjacent said emitting regions, and a layer of electrical insulating material extending between said control conductors and said emitting regions.
5. An emitting and display device as defined in claim 2 wherein each said emitting region is elongated, and said emitting regions are arranged in generally parallel spaced relation.
6. An emitting and display device as defined in claim 2 wherein said display screen is disposed in adjacent relation to said emitting regions.
7. An emitting device as defined in claim 1 wherein said display screen includes a phosphorous layer disposed generally adjacent said emitting surface of said emitting region, a conductor layer adjacent said phosphorous layer and having at least partial transparency, and a generally transparent insulator for supporting said phosphorous and conductor layers.
8. An improved solid state emitting and display device comprising a substrate, a cathode including a film body of side band gap semiconducting material on said substrate and having an outer surface, a plurality of emitting regions arranged in a generally planar array and projecting into said film body from said outer surface, each said emitting region comprises a narrow band gap semiconducting material having a resistivity higher than that of said film body material and having an emitting surface interrupting said outer surface of said body, a plurality of contacts on said film body and spaced with said emitting regions therebetween for applying a voltage across each said emitting region in a direction substantially perpendicular to a reference plane extending generally through the center of said emitting region generally normal to said outer surface of said film body, each said emitting region being effective to produce a continuous emission of electrons from said emitting surface without an applied external collection field in response to the application of a voltage to the corresponding said contacts, a display screen positioned adjacent said array of emitting regions and having a portion effective to emit light in response to the emission of electrons from a corresponding said emitting region, and means for selectively controlling the emission of light from each portion of said screen corresponding to each said emitting region.
9. An emitting device as defined in claim 8 wherein

said latter means comprise means for selectively controlling the emission of electrons from said emitting regions.

10. An emitting device as defined in claim 9 wherein said means for selectively controlling the emission of electrons from said emitting regions comprise a

plurality of control conductors arranged in generally parallel relation adjacent said emitting regions, and a layer of electrical insulating material extending between said control conductors and said emitting regions.
